[57] ABSTRACT

This forge furnace has a rotary barrel with means to periodically rotate the barrel and thereby cause the stock therein to roll around.

A vibratory feed mechanism is provided at the material inlet end to move the stock longitudinally when the barrel is not rotating.

Molded refractory inserts are placed in the barrel to provide passageways for the stock and the heating gases.

A stationary compartment with burners that produce a reducing gas mixture is provided at the stock outlet end.

FORGE FURNACE

CROSS-REFERENCE TO RELATED APPLICATIONS

This application is a continuation-in-part of the application of Sigdon A. Eliot, the inventor herein, Ser. No. 083,097 filed Oct. 22, 1970 and allowed Mar. 17, 1972, now abandoned.

BACKGROUND

The invention relates to the continuous heating of objects, and more particularly relates to the heating of forging stock prior to its being forged.

The forging of stock into articles requires that the stock be initially heated to a temperature, such as 2,100° F., before it is inserted into the forge and hammered to shape. The correct practice is to lay the bars of stock parallel and side by side on the horizontal flat hearth of an open front slot type furnace. Such a furnace has gas or oil burners at opposite ends which apply heat transversely to the bars. The furnace is located near the forge. Stock is laid on the hearth and heated until it reaches the desired temperature. Then the bars of stock are removed by an operator one by one and forged.

This system of heating the stock prior to forging has several disadvantages which the invention overcomes. The fuel is inefficiently used. The burning gases, ignited at the burner, pass immediately over the bars and are exhausted into the atmosphere. They are exhausted at a temperature very close to their maximum temperature so that a substantial quantity of the heat capacity of the fuel is lost.

Stock heated by laying on a hearth is not uniformly heated. The portions of each bar which contact the hearth will not be as hot as those portions exposed directly to the burner flame. When such bars are positioned side by side, each bar is in the shadow of one or more of the others. This, of course, blocks radiation to portions of the bars.

The open front of the conventional furnace permits the entry of oxygen-containing air. As hot gases escape upwardly by convection, air enters the lower part of the opening and contributes to the oxidation-scaling of the bars and a consequent deterioration of quality.

Therefore, it is an object of the invention to provide an improved forge furnace.

A further object is to provide a forge furnace which more efficiently utilizes its fuel.

A further object is to provide a forge furnace which uniformly heats bars of forging stock.

Another object is to provide a forge furnace which nearly eliminates the scaling of forging stock.

Yet another object is to provide for automatic control of both the bar stock delivery rate and the bar stock temperature.

Further objects and features of my invention will be apparent from the following specification and claims when considered in connection with the accompanying drawings illustrating several embodiments of my invention.

SUMMARY OF THE INVENTION

I have found that the foregoing and other objects may be attained in a furnace having a substantially horizontal, rotatably mounted barrel in the nature of a tumbler

barrel, although the forging stock or billets roll rather than tumble; a drive means for at times rotating the barrel and thereby rolling bars of forging stock around the interior of the barrel or around the interior of each of the concentric tubular passageways without substantial longitudinal movement of the stock; means for at times moving the stock longitudinally along the barrel; heating means for supplying heat into the end of the barrel out of which the heated stock is delivered either from one burner or two or more burners; means for supplying heat in the form of a reducing gas mixture at the forging stock outlet end of the furnace where the temperature is highest so that said reducing gas surrounds the stock and moves toward the object inlet end; means for mixing an oxidizing gas mixture or pure air with the reducing gas mixture at a portion of the furnace farther from the outlet end thereof where the forging stock temperature is lower and thus is not as susceptible to scale formation so that complete combustion is achieved while at the same time scale is substantially eliminated; and means for increasing the capacity of such a furnace without excessive length by providing a plurality of longitudinally extending passageways concentrically around the core of the furnace.

Further objects are obtained by utilizing a preheat oven, positioned to receive heat from the end of the barrel, in which the bars of stock can be stacked and from which they can be injected into the tumbler barrel.

Still further objects are obtained in a refractory furnace core or liner for use in an outer furnace shell, the liner comprising a hollow refractory core having an inner wall portion defining the inner wall of the furnace and an outer wall portion which is supported by and spaced from the shell and held at a uniform distance therefrom.

DESCRIPTION OF THE VIEWS

FIG. 1 is a plan view of one embodiment of the invention;

FIG. 2 is a view in side elevation of the embodiment of FIG. 1;

FIG. 3 is a view in vertical section taken substantially along the line 3-3 of FIG. 2;

FIG. 4 is a view in side elevation of the furnace shown in FIG. 2 being fragmentary and showing the outlet end of the barrel, the burner and the trap door, being taken from the opposite side of the side elevation of FIG. 2 and having parts broken away and shown in section;

FIG. 5 is a view in side elevation of a fragment of the furnace shown in FIG. 2 looking at the furnace from the opposite side of the side elevation of FIG. 2 and having parts broken away and shown in section;

FIG. 6 is a view in vertical section taken along the line of 6-6 in FIG. 5, further illustrating the structure;

FIG. 7 is a view in end elevation of a refractory insert constructed according to the invention and used in the embodiment shown in FIGS. 1, 2, 3, 4, 5, and 6;

FIG. 8 is a view in side elevation of the insert illustrated in FIG. 7;

FIG. 9 is a schematic view of the control circuit used to control the operation of the embodiment illustrated in FIGS. 1-8;

FIG. 10 is a view in plan similar to FIG. 1 but showing a different embodiment of my invention;

FIG. 11 is a view in end elevation of the embodiment of FIG. 10 taken substantially on the line 11-11 of FIG. 10;

FIG. 12 is a view in side elevation of the furnace shown in FIG. 10;

FIG. 13 is a fragmentary view in perspective of a portion of the embodiment of the furnace shown in FIG. 10 being on an enlarged scale and having sections broken away so as to show the core of the furnace and other interior elements;

FIG. 14 is a view in perspective showing one of the core ceramic inserts of the embodiment of the invention shown in FIG. 10;

FIG. 15 is a fragmentary view in perspective with parts broken away to further illustrate the construction of the casing of the furnace shown in FIG. 10;

FIG. 16 is a fragmentary view in vertical section and on an enlarged scale taken substantially on the line 16-16 of FIG. 11;

FIG. 17 is a fragmentary view in enlarged vertical section taken substantially on the line 17-17 of FIG. 10; and

FIG. 18 is a view in vertical section taken substantially on the line 18-18 of FIG. 17.

In describing the embodiments of the invention illustrated in the drawings, specific terminology will be resorted to for the sake of clarity. However, it is not intended to be limited to the specific terms so selected, and it is to be understood that each specific term includes all technical equivalents which operate in a similar manner to accomplish a similar purpose.

DETAILED DESCRIPTION

FIGS. 1 and 2 illustrate one assembled embodiment of the invention. A substantially horizontal rotatably mounted barrel 10 is supported on a plurality of pairs of rollers such as 12a, 12b, 12c, 12d, 12e, 12f, 12g, and 12h. These rollers are rotatably mounted in support arms 14 which are welded to an underframe 16. Three top rollers 18a-18c are mounted on substantially horizontal beams 20a-20c which are held above the barrel 10 by vertical struts such as vertical strut 22 (FIG. 2). Thus the rollers 12a-12h, together with the rollers 18a-18c, prevent radial movement of the barrel 10 and keep it cradled above the underframe 16.

A pair of annular flanges 24 and 26 are welded to the exterior of the barrel 10 and seat against a pair of horizontally rotatable wheels 28 and 30 (FIG. 2) located beneath the barrel 10 to prevent longitudinal movement of the barrel. The barrel 10 is rotatably driven by a motor 32 which is connected by suitable sprocket wheels and a drive chain 34 to the barrel 10.

The underframe 16 rests on a plurality of transverse horizontal channel members 36a-36f which in turn are supported on a vibration platform 38. The platform 38 has legs 40a-40c which are mounted on a base 42. A vibratory conveyor drive 44 using eccentric weights is mechanically linked by an arm 45 to the vibration platform 38 and is belt driven by a motor 46. The vibratory drive at times longitudinally vibrates the barrel 10 to move objects longitudinally through the barrel.

At the outlet end 48 of the barrel 10 is a stationary cylindrical compartment 49 to which a gas burner heating means 50 is mounted. Fuel is supplied to the burner 50 through a supply pipe 52. The compartment 49 is mounted on a standard 54 (FIG. 2) and is provided with a trap door 56 which is periodically opened to per-

mit objects heated in the barrel 10 to drop out. This structure is shown in more detail in FIG. 4 and is described in more detail below.

The bar stock absorbs approximately 80 percent of its heat energy from radiation. Relatively little heat comes from conduction from the gases. Consequently, and especially because the heat transfer by radiation varies as the cube of the temperature (i.e. T^3), it is desirable to heat the inner walls of the barrel 10. Therefore, a burner may advantageously comprise two parts: one which directs a slightly oxidizing flame (maximum heat) at a slight angle against the top inner surface of the barrel; the other would direct a reading flame (to reduce scaling) directly along the barrel. This provides a dual heat layer of gases which will join further down the tube to, in effect, extend the flame front along the barrel.

A preheat oven 70 is positioned to abut the inlet end 72 of the barrel 10 and is inclined to rise therefrom. Objects such as forging bar stock may be stacked in the preheat oven 70 and be preheated by the hot gases passing from the barrel 10 through the preheat oven 70.

The bottom of the preheat oven 70 is an inclined platform 74 (see also FIG. 5) which extends approximately radially upwardly and outwardly from the central axis of the barrel 10 and is covered on its top and sides by a cover means 76 to form an enclosed inclined passageway. Objects such as forge bar stock 112 can be stacked as shown in FIG. 1 and FIG. 5. Injection means, such as pneumatic cylinders 80 and 82 (FIG. 2), are mounted at the lower end of the oven 70 near the abutting barrel 10 for selectively injecting the stacked objects from the preheat oven 70 into the barrel 10 as described in more detail below and illustrated in more detail in FIG. 5.

FIG. 4 shows in greater detail the stationary compartment 49 which abuts and opens into the barrel 10. The barrel 10, the compartment 49, and the burner 50 are lined with a suitable refractory such as 90, 90A and 90B. The refractory of the barrel 10 should have a substantially cylindrical inner surface so that during rotation of the barrel 10, the bar stock, designated 92 in FIG. 4, will roll smoothly around the interior surface. It will not actually tumble, although the barrel 10 may be at times referred to as a tumbler barrel. In this specification and in the claims, the words "tumbler barrel" are to be construed to mean a rotatable cylinder in which material moves around the cylinder while the cylinder rotates whether it tumbles or not.

A trap door 56 is mounted by a hinge 94 to the underside of the stationary compartment 49. It has a counterweight 51 holding it closed. The door 56 may be opened, by a suitable device, such as a solenoid or a foot pedal, but I prefer a pneumatic cylinder 53 the plunger of which is connected by a hinge pin 55 to an arm 57 extending from the trap door 56.

An infra-red radiation-sensing temperature recorder 61 and its sighting tube 63 are mounted to the stationary compartment 49.

When the vibratory conveyor drive 44 (FIG. 2) is activated, the bar stock 92 moves toward and into the stationary compartment 49 until it falls, by gravity, onto the trap door 56. The weight of the bar stock 92 will move the door to the position 56A where it will be held by the pneumatic cylinder 53 for a short period of time. While resting on the trap door and laying in the center

of the cylindrical wall, the bar of stock will have its temperature measured and recorded by the temperature recorder 61 with its sighting tube 63. Then the pneumatic cylinder 53 will be activated to move the trap door to the position 56B permitting the bar stock to fall onto a table (not shown). An operator will lift it from the table and position it in the forge.

The temperature read by the temperature recorder 61 will also provide a temperature controlling signal. It is used with a conventional feedback control system which will control primarily gas valve and secondarily the cycle period.

A viewing window 100 is mounted at one end of the stationary compartment 49 to permit viewing of the contents of the barrel 10 and the burner flame. The viewing window 100 is mounted in a tube 102 which is hingedly mounted to the stationary compartment 49 so that it can be opened for igniting the flame.

FIG. 4 and FIG. 5 respectively supplement FIGS. 1 and 2 to illustrate the compartment 49 as described above and the preheat oven 70 and the injection means for selectively injecting bar stock or other objects from the preheater into the tumbler barrel. The inclined platform 74 and its enclosing cover 76 extend upwardly and radially away from the barrel 10 at an angle of about 45° to form the preheat oven 70. For large stock, the angle should be decreased — for example, to about 25°. The oven 70 is lined with a suitable refractory 104 to form an enclosed passageway through which hot gases from the tumbler barrel pass. The hot gases enter the preheat oven through an opening 106 in the oven 70 which is opposite the inlet end 72 of the barrel. A ceramic stop 110 on the bottom of the preheat oven 70 retains stacked bar stock 112 which can be stacked along the inclined surface to the upper end (FIG. 1) of the preheat oven 70.

As seen best in FIG. 6, a pneumatic cylinder 80 is mounted beneath the preheat oven 70 near the stop 110. Its plunger 81 extends to a position immediately above the stop 110 so that when the pneumatic cylinder 80 is actuated, its plunger 81 pushes one bar stock (designated as 112 in FIG. 6) above the stop 110. The bar 112 then falls to the position 112A (FIG. 5 and 6) against a second stop 114.

Returning to FIG. 5, the bar stock at position 112A is now positioned to be injected into the tumbler barrel 10 by the plunger 83 of the pneumatic cylinder 82. This injector plunger 83 is mounted approximately parallel to the longitudinal axis of the barrel so that, when actuated, it will strike the end of the bar stock at 112A and inject it into the inlet end 72 of the tumbler barrel 10. At the bottom end of preheat oven 70, I have provided a door 116, visible in FIG. 6, which is mounted by a hinge 118 to the preheat oven 70. This door provides access to the inside of the preheat oven 70 for inspection or repair. In operation, the door 116 is kept closed and latched.

In FIG. 5, the section of the preheat oven is shown to be rectangular. However, it will be desirable in some circumstances to provide a trapezoidal cross section in order to provide heat transfer with improved uniformity. For example, the side wall 301 might be shortened so that the top 303 would be inclined downwardly from left to right in FIG. 5. This would cause the gases, which flow from the barrel 10 and turn up the preheat oven 70, to more uniformly transfer their heat to the walls of the preheat oven 70.

It may also be desirable at times to provide an additional separate heater for heating the preheat oven. Such an additional heater would be useful in initially warming up the preheat oven and also would make increased delivery rates possible.

As another alternative, the preheater might have a plurality of small parallel passages through which bar stock is pushed, as by a plunger to feed the tumbler barrel 10.

10 Still another alternative is a longitudinal preheater with several (such as seven, for example) longitudinal, parallel, tubular passages extending through it, each one containing bars being heated. Such a preheater is substantially coextensive, with and is positioned parallel to the barrel 10 and next to it. Thereby much space is saved by the compactness of the unit. If desired, the longitudinal preheater may preferably be cylindrical. Also if desired, a suction fan may be used to suck the heated gases through the preheater.

20 Means are provided for rotating the longitudinal preheater similar to the means shown for rotating the barrel. However, though the barrel and the preheater may rotate at identical speeds, the preheater may be rotated faster or slower. In the machine which I have built, the preheater rotates continuously. It is not necessary to have the preheater pause for the vibration period of the barrel. Means are provided for causing the objects to be heated to move from the inlet end of the preheater to the outlet end thereof.

30 A properly designed transfer box is provided to transfer the preheated bars from the longitudinal preheater to the barrel.

Such a transfer box should be intermediate the preheater 74 and the rotating barrel 10.

The design of the transfer box is very like the design of the preheat oven 70 as shown in FIGS. 1, 2 and 6. It is much shorter than the preheater 70 and only constitutes means for moving the objects from the outlet end of the preheat oven into the inlet end of the barrel. 40 In my construction this last mentioned means includes a pneumatically operated plunger very like the plunger associated with pneumatic cylinder 82 shown in FIGS. 1, 2, and 5. This plunger is arranged and controlled to be automatically operated as each of the longitudinal parallel tubular passages of the preheater becomes aligned with the plunger. The transfer box does not have a stop similar to stop 110 nor a pneumatically operated cylinder and plunger similar to 80 and 81.

50 The forging stock (such as bars, for example) are fed cold into the preheater. Such feeding may be done manually. However, I prefer that this be done automatically and in the furnace which I have built I have provided automatic means for feeding forging stock bars into the preheater.

55 Adjacent the inlet side of the preheater, I provide a sloping platform or shelf. On the opposite side of the platform from the preheater, I provide a pneumatic cylinder similar to cylinder 82 and having a pneumatically operated plunger. Bars are fed automatically by gravity to this platform one at a time so that when any longitudinal passageway of the preheater becomes aligned with the plunger, the bar on the platform is also aligned between the plunger and the passageway of the preheater. Actuation of the plunger when the passageway of the preheater becomes aligned pushes the bar off of the platform and into the passageway of the preheater and thus pushes all other bars in that passageway for-

ward therein. Thus a bar will be deposited at such time into the transfer box and so fed into the furnace barrel 10 when desired. Controls are provided so that this action takes place only when a bar is released from the barrel furnace. It is to be understood that the circumference of each passageway is not equal to nor an exact multiple of the circumference of the bar so that as the preheater rotates, the bars (at the time of alignment with the plunger) do not rest on the same side as before and are thus not subject to excessive abrasion.

The advantages of rotation of the preheater are several. For example (1) inasmuch as heat rises, were there not rotation, the forging stock object at the top would be heated more intensively than forging stock objects at other positions; (2) inasmuch as the forging stock objects would without rotation always lay on the same side, pushing the stock through the preheater would tend to abrade that side; and (3) if the forging stock continued to lay on one side, that side would be shielded against radiant heat and the stock would be heated unevenly and more slowly.

Where lengthwise space is not critical, the preheater cylinder may be in line with (instead of side by side of) the barrel. This utilizes a long narrow space and eliminates the necessity of a transfer box.

In FIGS. 7 and 8, the details of one form of refractory inserts which I have developed for use in the tumbler barrel 10 are illustrated. However, such refractory inserts could also be utilized in other furnace structures and other forms as later disclosed could be used in furnace 10. In phantom, in FIG. 7 is shown the outer furnace shell 120 which, as illustrated, is the shell of the tumbler barrel 10. A hollow refractory core 122 fits snugly within the shell 120 and has an inner cylindrical wall portion 124 defining the inner walls of the furnace and has outwardly extending spaced legs 126A, 126B, etc. extending into contact with the shell 120. These legs 126A, 126B, etc. rigidly support the core 122 in the shell 120. The spaces 128A, 128B, etc. between the legs, the inner wall 124, and the shell 120 are filled with insulation, which I prefer to be diatomaceous earth.

My structure secures the advantages of the rigidity and hardness of a refractory, such as alumina, and the excellent insulating properties of a soft material like diatomaceous earth.

When used in the tumbler barrel 10, a series of identical inserts are mounted end to end along the cylindrical shell of the barrel. Preferably, their legs are aligned so that the insulation can be easily filled in after all the inserts have been mounted in the shell.

OPERATION AND THE CONTROL CIRCUIT

Each step of the following described operation could be manually initiated in a manner which should be obvious. For example, each electrical device, pneumatic device and mechanical device could be manually operated by means of switches, valves and levers. The preferred operation, described generally, begins with the stacking of stock in the preheat oven 70 and the ignition of the burner 50.

After the equipment is brought to operating temperature, a bar of stock is injected or inserted into the barrel 10 by the pneumatic cylinders 80 and 82. The vibratory drive is activated and stock is periodically injected into the barrel until the barrel is filled with a series of longitudinally spaced bars of stock.

At this point the rotary drive begins and the vibratory drive ceases. The bars will then simply roll around the interior of the barrel and become evenly heated. At desired intervals, rotation is halted and vibration initiated until a bar falls out the trap door. Then a new bar is injected, vibration halted, and rotation begun until another heated bar is desired.

FIG. 9 illustrates the control circuit I prefer to use to automatically operate the apparatus described above.

10 The operation of the preferred automatic embodiment is now described simultaneously with the description of the control circuit.

Control circuit power is applied at terminals T1 and T2 and fused by a fuse 202. A master-start-stop circuit 15 is provided in which contacts RL2B close to apply power to the control circuit. When the master-start control button 204 is depressed, relay RL2 is energized and both the latching contacts RL2A and contacts RL2B are closed to energize the circuit. A pilot light 20 LT1 indicates the energization of RL2. The whole system is shut down by depressing the normally closed master-stop button 206 thereby de-energizing RL2.

When contacts RL2B close, and with the automatic operation switch 208 closed, power is applied to the timing circuitry. This occurrence is indicated by a pilot light LT2. Timer T2 is immediately energized through normally closed contacts RL1A. The mode of operation of the timer T2 is such that after a short time delay after it is energized, it closes the contacts T2A.

30 Closing the contacts T2A energizes the main timer motor and clutch TM1 and TC1 respectively which in turn immediately closes contacts T1A and T1B. The closing of contacts T1A latches the timer T1 so that when contacts T2A open (when contacts RL1A later open) the timer T1 will still remain energized.

When contacts T1B close, the vibration motor starter MS2 and the timer TM3 are energized through the normally closed contacts RL1B. Control panel pilot light LT3 is also illuminated. At this point, vibration of the barrel begins and the bars of stock begin moving longitudinally along the barrel. The timer TM3 is a warning device which, as will be apparent, will close contacts T3 to cause visible and audible signals LT7 and HR to be actuated if no bar of stock has fallen from the trap door 56 within a specified time, such as 7 seconds.

45 With the vibration motor now operating, the bars of stock will be moving toward the stationary compartment 49. The vibration motor will continue and the control circuit will remain in the same state until a bar of stock falls onto the trap door 56 and moves it to its position 56a. A limit switch LS1 (see FIG. 2) is mounted beside the trap door 56 so that it is actuated when the trap door moves to the position 56a. Thus, in summary, the vibration motor continues until a bar of stock falls onto the trap door 56 and thus closes the normally open contacts of the limit switch, those contacts being LS1A and LS1B.

50 The closing of contacts LS1A energizes relay RL1 thus opening contacts RL1A and RL1B and closing contacts RL1C and RL1D. The opening of contacts RL1A de-energizes the timer T2 and thereby opens contacts T2A. However, the main timer T1 remains energized through contacts T1A. Simultaneously, the opening of contacts RL1B stops the warning timer motor TM3 and stops the vibration motor MS2. The closing of contacts RL1C latches relay RL1 to its energized position after contacts LS1A reopen. The closing

of contacts RL1D energizes the rotation motor MS1 and simultaneously illuminates the control panel pilot light LT4. Therefore, the effect of closing contacts LS1A is to stop the vibration motor, initiate operation of the rotation motor, and stop the warning timer TM3.

As stated above, when a bar of stock falls on the trap door, the contacts LS1B are also closed. Thus, simultaneously with the above activity, the timer motor T4 is actuated and, if the automatic feed control switch 299 is closed, power is applied to the solenoid SOL-1. Actuation of power to the solenoid SCL-1 causes operation of the stock injection means comprising the cylinders 80 and 82. The solenoid SOL-1 actuates the pneumatic circuit which causes the cylinders 80 and 82 to move a bar of stock to the position 112A and then inject it into the barrel and to retract to their original positions.

The timer T4 is for holding the bar of stock on the trap door while its temperature is being read by the temperature reading device 61. For example, the timer T4 might delay 2 seconds from the time contacts LS1B are closed until the contacts T4 are closed. The closing of contacts T4 actuates the solenoid SOL-2 which in turn trips the pneumatic circuit to actuate the pneumatic cylinder 53 and thereby open the trap door 56 to the position 56B, permitting the bar of stock to fall or roll onto a platform. An operator then lifts the bar of stock and positions it in the forge.

The trap door 56 opens until an arcuate cam (not shown) formed on the trap door 56 releases the limit switch LS1 so that contacts LS1A and LB1B may open. When contact LS1B opens, power is no longer supplied to timer T4 to hold contacts T4 closed nor is power supplied to solenoid SOL-1 and the trap door returns to its closed position without closing the contacts of limit switch LS1. The opening of contacts LS1A has no effect because relay RL1 is held energized by the latching contacts RL1C. The circuit will now continue in this state, with the rotation motor operating and the vibration motor not operating, so that the bars will roll around the interior of the barrel and continue to be uniformly heated, since it will continue in this state until the timer T1 has run for its set period of time. The length of time set in timer T1 determines the period of bar stock delivery through the trap door. Thus, if a bar is desired every 30 seconds, for example, the timer T1 is set for 30 seconds.

After the time set in timer T1 has elapsed, contacts T1A and T1B will again open. The opening of contacts T1A de-energizes the timer T1 and permits it to reset. The opening of contacts T1B de-energizes the motor circuitry for rotation motor MS1 and returns it to its initial states. Thus, opening of contacts T1B de-energizes the relay TL1 therefore closing contacts RL1A and RL1B and opening contacts RL1C and RL1D. This instantly reapplies power to time delay timer T2 to begin the cycle again. The delay in timer T2 is to permit a sufficient time for the timer T1 to reset itself.

Where desired, counters CR1 and CR2 may be positioned as shown to count one unit each time contacts T1B are closed. Thus the counters will count the cycles of operation and therefore the number of bars of stock which pass through the trap door. Counter CR1 can be reset at will to count the number of units of a particular job. Counter CR2 counts the total cycles the apparatus has operated.

The embodiments shown in FIGS. 10-18 inclusive area are in many respects similar to the embodiments shown in FIGS. 1-9. However these embodiments of FIGS. 10 to 18 differ in other respects and these differences constitute important improvements over the structure shown in FIGS. 1-9 inclusive.

The several embodiments disclosed all show the combination of a rotatable furnace for the continuous heating of objects with means for rotating the furnace and 10 with separate means for causing longitudinal movement of objects placed in the furnace along the barrel thereof from the inlet end toward the outlet end as well as heating means for supplying heat into the furnace. All of the embodiments disclose a compartment opening 15 into the outlet end of the barrel, mounted abutting the barrel for receiving objects from the barrel and having a trap door for permitting objects to drop from the compartment. All of the embodiments disclose electrical controls for at desired times causing the rotatable barrel to be rotated and at times for causing the barrel 20 to stop and at times when the barrel is stopped from rotating causing the insertion or injection of objects to be heated into the barrel, the removal of objects from the barrel and/or the movement of objects along the length of the barrel.

All of the embodiments disclose the rolling of the objects around the interior of the bores through the furnace so that the objects are heated uniformly and so that the objects when moved longitudinally do not always move while supported by the same side of the object. This eliminates undue wear on one side. All of the embodiments disclosed have electrical controls for starting and stopping the rotation of the barrel and for energizing the means for inserting objects to be heated 30 into the barrel, for removing heated objects from the barrel and/or moving the objects being heated from one end of the barrel to the other during the time that the barrel is stopped from rotating. All of the embodiments disclose an arrangement wherein the inner core 35 of the barrel is formed by a plurality of aligned segments of a ceramic material.

However, in the embodiment shown in FIGS. 10-18 no means are provided for longitudinally vibrating the barrel to achieve longitudinal movement of the objects 45 along the barrel from the inlet end to the outlet end. Moreover in the embodiments shown in FIGS. 10-18 there are shown a plurality of passages extending through the rotating barrel whereby the capacity of the furnace is greatly increased to the extent of approximately the product of the capacity of a single bore furnace multiplied by the number of bores provided. In order to minimize scaling it is desirable to have the objects heated by a non-oxidizing flame at the time that they are at the highest temperature and by an oxidizing flame only at the time that they are at a relatively low temperature whereby scaling is substantially eliminated. Therefore in the embodiments shown in FIGS. 10-18 an oxidizing stream of heating gas and a separate reducing stream of heating gas is injected into the furnace. Means are provided so that only the reducing stream contacts the objects being heated when the objects are at a relatively high temperature but the two streams mix to achieve complete combustion.

With the above in mind and referring especially in 65 FIGS. 10-12 inclusive, it may be seen that I have shown therein a substantially horizontal rotatably mounted barrel 410 supported on a plurality of pairs of rollers

such as rollers 412a and 412b which are mounted in support arms 414 which are in turn welded to an under-frame 416 consisting of upper horizontal members such as 418 supported by vertical struts such as the vertical strut 420 which are in turn supported by the base 422. The barrel 410 is rotatably driven by a motor 432, by a chain 434 in a manner similar to the apparatus shown in the embodiment of FIGS. 1-9 inclusive. At the outlet end 448 of the barrel 410 is a stationary compartment 449 to which a pair of gas burner heating means 450 and 451 are mounted. Fuel is supplied to the burners 450 and 451 through supply pipes which are not shown. The compartment 449 is mounted on frame 416 and is provided with a trap door 456 (See FIGS. 17 and 18) which is periodically opened to permit objects heated in the barrel 410 to roll out. It may be noted at this point that the trap door unlike the trap door of FIGS. 1, 2, and 4 is mounted on a hinge 457 which has its axis extending parallel to the longitudinal axis of the furnace whereby the objects roll out when the door is opened rather than fall out.

The trap door 456 may be provided with a counter-weight as is shown in FIG. 17 at 454 and necessarily is provided with a pneumatic control cylinder 455 as is shown in FIG. 18. It is true, the arrangement of the trap door 56 shown in FIGS. 1, 2, and 4 may be used if desired. However, I prefer very much to use the arrangement shown in FIG. 18 inasmuch as thereby distortion of the billets as they roll from the compartment 449 is minimized or eliminated entirely.

The arrangement of a preheater for loading objects such as billets into the furnace barrel 410 as shown at 70 in FIGS. 1, 2, and 5 may be used if desired. However, in view of the improvements in the furnace barrel 410 such a preheater is oftentimes unnecessary and the arrangement as shown in FIGS. 10 and 12 for loading billets into the furnace barrel 410 is in most cases satisfactory.

The utilization of a preheater having a plurality of longitudinal passages extending therethrough and arranged parallel to and adjacent to the rotor furnace barrel 410 as described above on pages 13, 14, and 15 hereof can be used with the furnace barrel 410 if desired. A transfer box as described in connection with the parallel arranged preheater may also be used if desired. However, as stated above the arrangement shown in FIGS. 10 and 12 is normally satisfactory. Therein billets are placed upon or are allowed to roll down into proper position on a shelf 470 (FIG. 12) where they can be at the proper time injected into the furnace barrel 410 by means of a plunger 483 operated by means of a pneumatic cylinder 482.

One very important feature and advantage of the furnace shown in FIGS. 10 to 18 inclusive is the arrangement by which the capacity of the furnace barrel 410 is increased many fold over the capacity of the furnace 10 (FIG. 1). Referring to FIGS. 11, 13, 14, and 17 especially, it may be seen that the furnace barrel 410 comprises an outer casing or shell 411 which may preferably be of metal. Positioned concentrically within the casing 411 is a ceramic core generally designated as 413. The core 413 is provided with a plurality of longitudinal passageways such as passageways 415a, 415b, 415c, 415d, etc. As shown there are eight passageways clearly shown in FIGS. 11, 13, and 14. When the furnace is operating these passageways are all filled with objects to be heated. Therefore for an equivalent

length the furnace 410 has eight times the capacity of the furnace 10 of FIG. 1 wherein there is provided only one passageway. If a greater capacity is desired the number of passageways 415 could be increased if desired. During all the time that the objects to be heated are in the passageways they are being heated by gas which is supplied into the furnace as will later be described more in detail, and consequently a much larger number of objects is being heated at the same time. The 10 objects to be heated are supplied into the furnace one at a time in one of the passageways. For example, when the furnace barrel 410 is in the position shown in FIG. 11 and a billet lies upon the table 470 (FIG. 12) and the furnace barrel is stopped from rotating, actuation of 15 the cylinder 482 through the plunger 483 pushes the billet into the passage 415d. If then the furnace is rotated clockwise as for example, through 180° and is stopped, the cylinder 482 may be actuated to push another billet by means of a plunger 483 into the passageway 415a. If the furnace barrel is again rotated through 45° and stopped, then the cylinder 482 and the plunger 483 may be actuated to push another billet into the passageway 415b. Similarly if the furnace barrel is rotated through an additional 45°, etc. and stopped the cylinder 25 482 and the plunger 483 may be actuated to push a billet into the passageway 415c, etc. The electrical system subsequently to be described is so programmed that billets are alternately pushed into each of the passageways so that all of the passages of the furnace are filled 30 and each of the billets remains in the core of the furnace for an identical length of time. As each billet is pushed into one of the passageways as may be understood especially from FIG. 17, all of the billets in that same passageway as for example, in passageway 415d, 35 are moved toward the outlet end and one is pushed into the outlet box or receptacle 449 (FIGS. 10 and 12). The billet 417a is shown in dotted lines in the receptacle 449. When the cylinder 455 is actuated to open the trap door 456 the billet 417a will roll on the trap door 456 to an outlet position such as is shown full lines at 417b. The plunger 483 may thus push a billet from the table 470 (FIG. 12) into the passageway 415d (FIGS. 11 and 17). This billet will gradually pass through the furnace and eventually will be pushed out as at 417a and when the door 456 is opened will roll on the door as at 417b and thus be released from the furnace barrel. 40 As shown most clearly in FIG. 17 the core 413 is spaced concentrically in the furnace barrel 410 and is held securely in place by a plurality of screws such as the screws 426a, 426b, 426c, and 426d as shown in FIG. 17. As indicated in FIG. 13 there are also other identical screws placed circumferentially around the circumference of the core 413. It will be noticed that the core generally designated as 413, consists as shown 45 in FIGS. 13, 14 and 17 of a plurality of separate ceramic sections such as the sections 421a, 421b, 421c and 421d. These are also held in place by the screws such as the screws 426a-426d inclusive referred to above. The passageways 415a, 415b, 415c, 415d, etc. in each of the segments are aligned with each other and held in alignment by said screws, and thus each passageway forms one continuous passageway through the whole core. The core is also provided with a central passageway 407 (FIG. 17) which is much larger than the passageways 415a, etc. The axis of the passageway 407 is on the axis of rotation of the furnace barrel. The axes of the passageways 115a, etc. are arranged in a cir-

cle which is concentric with the axis of passageway 407. As the furnace barrel rotates, the axis of each longitudinal passageway 415, etc. at times is aligned exactly with the billet which lies upon the table 470.

Another important feature of the furnace disclosed in FIGS. 10-18 is the means which I have devised for preventing scale on the objects being heated, regardless of the fact that the objects are heated at high temperatures. I accomplish this prevention of scale with most efficient combustion so as to produce the maximum amount of heat from the fuel used. It will be noticed that as shown in FIGS. 10, 12, and especially in FIG. 17 there are two burners 450 and 451. Each of these supplies a combustive mixture of combustible gas and air or oxygen but the mixture of air or oxygen and gas differs in the two burners. In one case the mixture supplied by burner 450 is a reducing mixture and in the other case, the stream of combustible mixture supplied by the burner 451 is an oxidizing mixture. Pure heated air or pure oxygen could be supplied instead of a mixture from 451 but for practical purposes I prefer to supply an oxidizing combustible mixture of air and gas from the burner 451. This oxidizing mixture supplied from the burner 451 flows into the central passageway 407 (see FIG. 17) until it reaches the ceramic block 403 positioned adjacent the inlet end of the barrel 410. The pressure of combustible gas naturally builds up in the passageway 407 and increasing increments of the burning oxidizing mixture spread out through openings such as 406a, 406b, 406c, and 406d into the passageways 415a, 415b, 415c, 415d, etc. The burning oxidizing gas mixes with the burning reducing gas mixture coming from the burner 450.

Thus the billets such as 417c as they are first introduced into the furnace at the inlet end are relatively cool and are initially heated by a mixture of the oxidizing stream and the reducing stream. Although the mixture of the oxidizing stream and the reducing stream. Although the mixture is intended to be stoichiometric at this time, were the billets relatively hot, there would be some danger of scaling. However the billets have not yet been heated to a very high temperature and scaling is avoided. However as the billets proceed through the passages 415a, 415b, 415c, and 415d, etc., the heating mixture of combustible gases becomes more and more reducing and when the billets approach the outlet end of the furnace, there is no danger of scaling because of the reducing gas surrounding the billets entirely as an envelope. That is to say, that as the billets proceed toward the outlet end of the barrel 410 they are gradually heated to their highest temperature and at the outlet end of the furnace where they are at their highest temperature the gas mixture coming from the burner 450, is decidedly reducing and there is little or no tendency to oxidize at this point and form scale. The amounts of gas mixtures are such that the total mix is stoichiometric and complete combustion is achieved. For example, I may supply a mixture of gas and air through the main center burner nozzle 451 which consists of an excess of air gas, for example, a mixture of gas and air with an excess of air (or deficiency of gas) of 10 percent. Through the second burner 450 I supply to all of the passages 415a, 415b, 415c and 415d, etc., a mixture which has an excess of gas (or a deficiency of air) of about 50 percent. In the example given the lean mixture with the 10 percent excess of air is supplied by the central burner 451 into the central pas-

sageway 407 and rich mixture with the 50 percent excess of gas is supplied into the several circumferential passageways 415a, etc. However in order to achieve full combustion in this example we would supply a relatively large volume of the lean mix with the 10 percent excess of air and a relatively small volume of the rich mix with the 50 percent excess of gas so that when the two are mixed together there will be an exact stoichiometric balance and complete combustion.

Referring now especially to FIG. 16 for a description of the structure of the rotating barrel 410 and the inner core 413 thereof, it may be seen that there is provided a steel casing or shell 411 through which the screws 416, etc. extend. The screws bear on metal strips 404a which are secured to a stainless steel skin 409 (shown in FIG. 6) which may be of approximately 0.060 thickness and which surrounds the ceramic segments 421a, 421b, 421c, 421d, etc. which form the core 413 for the furnace barrel 410. Each ceramic segment may be formed of two different types of ceramic such as an insulating ceramic 405 and a high alumina ceramic 406 as shown in FIG. 16.

The electric controls are similar to the electric controls shown in FIG. 9 but they are modified so that they control the operation of the furnace to (1) stop the rotation of the furnace barrel at a position at which the billet on the platform 470 is aligned with one of the concentric passageways such as 415a; (2) then the control operates the pneumatic cylinder 482 to insert a billet into the passage 415a. This pushes the billets in that passageway forward and the billet next to the outlet end falls into the compartment 449. The electric controls (3) operate the door 456 to release the billet and (4) start the rotation of the furnace barrel. At the end of the time period for which each cycle is set (5) the controls stop the furnace barrel and the cycle repeats.

Means are provided (see FIGS. 13 and 15) for positioning the core 413 relative to the steel casing or shell 411. This means consists of a channel member 408 secured to the inner part of the shell 411 and a key or lug 408a on the core 413 which fits into the channel as shown in FIGS. 13 and 15.

Means are provided for minimizing the amount of gas, air and/or combustive mixtures which might otherwise escape through the slight space between the rotative barrel 410 and the unit which houses the burners 450 and 451 and the compartment 449. This means consists of a plurality of pipes 419 which supply fluid such as steam to exert a back pressure on the gas and combustive mixture and a shield 419a. The shield does not extend all of the way around the unit but the small gap at the position of the trap door 456 does not permit the escape of very much of such gas, air and/or combustive mixture inasmuch as the shield covers about 90 percent of the circumference of the barrel.

While the furnace has been described for example, as a furnace for heating forging billets so that they may be forged, it is clear that the invention as described and as claimed may be used for annealing or otherwise heat treating any suitably shaped objects.

It is to be understood that while the specific examples given describe preferred embodiments of my invention, they are for the purposes of illustration only, that the method of the invention is not limited to the precise details and conditions disclosed, and that various changes may be made therein without departing from the spirit

of the invention which is defined by the following claims.

I claim:

1. A furnace for the continuous heating of objects comprising
  - a. a substantially horizontal, rotatably mounted tumbler heater barrel having an object inlet end and an object outlet end;
  - b. means for at times rotationally driving the barrel for rolling the objects around the interior of the barrel without causing substantial longitudinal movement of the objects;
  - c. means for at times causing longitudinal movement of the objects along the barrel from the inlet end toward the outlet end;
  - d. a stationary compartment opening into the outlet end of the barrel, mounted abutting the barrel for receiving objects from the barrel, the compartment having means comprising a trap door for delivering heated objects from the compartment; and
  - e. heating means for supplying heated gases to said stationary compartment and from said compartment into the outlet end of the barrel.
2. A furnace for the continuous heating of objects comprising (a) a substantially horizontal, rotatably mounted tumbler barrel having an object inlet end and an object outlet end; (b) means for at times rotationally driving the barrel for rolling the objects around the interior of the barrel without causing substantial longitudinal movement of the objects; (c) conveyor type vibrating means for longitudinally vibrating the barrel to provide at times longitudinal movement of the objects along the barrel from the inlet end toward the outlet end; and (d) heating means at the outlet end for supplying heat into the outlet end;

wherein a stationary compartment opening into the outlet end of the barrel is mounted abutting the barrel for receiving objects from the barrel, the compartment having a trap door for permitting objects to drop from the compartment.
3. A furnace according to claim 2, wherein the heating means is a gas burner mounted to the compartment.
4. A furnace according to claim 3, wherein said burner has two portions with means for directing an oxidizing flame toward the inner surface of said barrel and means for directing a reducing flame along the barrel.
5. A furnace for the continuous heating of objects comprising (a) a substantially horizontal, rotatably mounted tumbler barrel having an object inlet end and an object outlet end; (b) means for at times rotationally driving the barrel for rolling the objects around the interior of the barrel without causing substantial longitudinal movement of the objects; (c) conveyor type vibrating means for longitudinally vibrating the barrel to provide at times longitudinal movement of the objects along the barrel from the inlet end toward the outlet end; and (d) heating means at the outlet end for supplying heat into the outlet end;

wherein a stationary, pre-heat oven opening into the inlet end of the barrel is mounted to abut the inlet end of the barrel and is inclined to rise therefrom, therein said objects may be stacked and preheated by hot gases flowing from the outlet end to the inlet end and thence through the preheat oven.

6. A furnace according to claim 5, wherein the preheat oven comprises:

- a. an inclined platform extending approximately radially upwardly and outwardly from the axis of the barrel; and
- b. cover means including a top and sides to form an enclosed passageway above the inclined platform;

wherein said objects may be stacked on the platform and heated.

7. A furnace according to claim 6,

wherein injection means are mounted to the lower end of the oven near the abutting barrel for selectively injecting bar stock objects from the platform into the tumbler barrel.

8. A furnace according to claim 7,

wherein the injection means includes an injector plunger mounted parallel to the longitudinal axis of the barrel opposite the inlet end of the barrel for movement toward the inlet end to inject a bar of forging stock from the preheat oven into the barrel.

9. A furnace according to claim 7, wherein the injection means includes:

- a. a stop protruding upwardly from the platform for preventing downward movement of bars of stock stacked in the oven; and
- b. an upwardly moving plunger mounted near the stop for pushing one bar of stock over the stop and into position for injection into the barrel.

10. A furnace for the continuous heating of objects comprising (a) a substantially horizontal, rotatably mounted tumbler barrel having an object inlet end and an object outlet end; (b) means for at times rotationally driving the barrel for rolling the objects around the interior of the barrel without causing substantial longitudinal movement of the objects; (c) conveyor type vibrating means for longitudinally vibrating the barrel to provide at times longitudinal movement of the objects along the barrel from the inlet end toward the outlet end; and (d) heating means at the outlet end for supplying heat into the outlet end;

wherein a preheat oven having an inlet end and an outlet end is provided and has its outlet end connected to the inlet end of the barrel; objects introduced into the inlet end of the preheat oven move from the inlet end of said preheat oven to the outlet end thereof; means are provided for moving the objects from the outlet end of said preheat oven into the inlet end of the barrel; and means are provided for conducting heated gases emerging from the inlet end of said barrel into and through the preheat oven whereby said objects are preheated by said heated gases which have flowed from the outlet end of said barrel to the inlet end thereof and then from the outlet end of said preheat oven to the inlet end thereof.

11. A furnace according to claim 10,

wherein the preheat oven is a longitudinal oven provided with a plurality of longitudinal passages into which objects being preheated may be placed, and is substantially coextensive with and is positioned parallel to the barrel.

12. A furnace according to claim 11,

wherein the preheat oven is cylindrical.

13. A furnace according to claim 10,

wherein means are provided for rotating said preheat oven.

14. A furnace according to claim 10,

wherein the preheat oven is stationary, is mounted to abut the inlet end of the barrel, and is inclined to rise therefrom, and wherein said objects may be stacked and preheated by hot gases flowing from the outlet end of the barrel to the inlet end thereof and thence through the preheat oven. 5

15. A method for uniformly heating bars of forging stock to forging temperature, the method comprising:

a. rolling the bars along the inner circumference of a tumbler barrel by effecting rotation of the barrel; 15

b. simultaneously passing suitably heated gases longitudinally along the barrel; and

c. periodically vibrating the barrel to convey the bars longitudinally along the barrel. 20

16. A method according to claim 15,

wherein the inner diameter of the barrel is substantially larger than the diameter of the forging bars. 25

17. A method according to claim 16,

wherein the barrel is rotated at approximately 1 revolution per minute. 25

18. A furnace according to claim 1

wherein the heating means is a gas burner mounted on and secured to the compartment. 30

19. A furnace according to claim 18,

wherein said burner has two portions with means for directing an oxidizing flame toward the inner surface of said barrel and means for directing a reducing flame along the barrel. 35

20. A furnace for the continuous heating of objects comprising:

a. a substantially horizontal, rotatably mounted barrel having an object inlet end and an object outlet end and having a plurality of separate passageways extending from the inlet end to the outlet end; 40

b. means for at times rotationally driving the barrel for rolling the objects in order to equalize the heating of the objects on all sides without causing substantial longitudinal movement of the objects; 45

c. means for inserting objects to be heated in one of said passageways and causing longitudinal movement of the objects along the passageway from the inlet end toward and out of the outlet end of the barrel; 50

d. means for inserting other objects to be heated into another of said passageways and causing longitudinal movement of the objects in said second passageway toward and out of the outlet end of the barrel; 55

e. means adjacent the outlet end of the barrel for receiving objects from the barrel; and

f. heating means for supplying heat into all of the passageways of the barrel. 60

21. A furnace according to claim 20,

wherein said heating means comprises: two burners one of which produced heated oxidizing products of combustion and the other of which produces heated reducing products of combustion; and wherein means are provided for directing a stream of products having oxidizing characteristics from one of said burners approximately longitudinally along a path longitudinally of said barrel and for directing 65

a stream of products having reducing characteristics from the other of said burners approximately longitudinally along a path longitudinally of said barrel spaced from and approximately parallel with the first mentioned path.

22. A furnace according to claim 20,

wherein there are produced two streams of heating gas, one of which is an oxidizing stream and the other of which is a reducing stream, and wherein the oxidizing stream is directed along a path extending approximately longitudinally of said barrel and not contacting the forging stock which is at a relatively high temperature and the reducing stream is directed along a separate path also extending approximately longitudinally of the barrel but spaced from and extending approximately parallel with the first mentioned path in such a way as to have this stream of reducing gas surround the stock which is at the relatively high temperature. 20

23. A furnace according to claim 22,

wherein the objects being heated which are at a relatively lower temperature are surrounded by a stream of heating gas which is approximately stoichiometric and therefore neither oxidizing nor reducing. 25

24. A furnace according to claim 22,

wherein there is only one burner but there are two streams of heating gas one of which is reducing and one of which is oxidizing. 30

25. A furnace according to claim 20, comprising:

1. an outer shell;

2. a hollow refractory core consisting of a liner for the outer shell; and

3. means for spacing the core from said shell and for rigidly supporting the core in said shell. 35

26. A furnace according to claim 25,

wherein the shell is cylindrical and rotatable and the core comprises a series of identically shaped inserts mounted in end to end relationship longitudinally along the cylindrical shell. 40

27. A furnace according to claim 25,

wherein the hollow core inner and outer walls are cylindrical and the means for spacing the core comprises spaced legs formed on the core as radially outwardly extending ridges. 45

28. A furnace according to claim 25,

wherein the means for spacing and supporting the core comprises:

a stainless steel casing surrounding the refractory core;

a plurality of slats secured to the casing; and

a plurality of threaded studs screwed through the shell and bearing on the outer surface of the slats. 50

29. A furnace according to claim 25,

wherein the core is substantially alumina. 55

30. A furnace according to claim 20,

wherein a preheat oven is mounted to abut the inlet end of the barrel. 60

31. A furnace according to claim 30,

wherein injection means are mounted at the lower end of the oven near the abutting barrel for selectively injecting objects to be heated into the barrel. 65

32. A furnace according to claim 31,

wherein the injection means includes an injector plunger mounted parallel to the longitudinal axis of 70

- the barrel opposite the inlet end of the barrel for movement toward the inlet end of the barrel to inject bars of forging stock into the barrel.
33. A furnace according to claim 31, wherein a platform is provided for storing bars of stock and the injection means includes:
- a top protruding upwardly from the platform for at times preventing downward movement of bars of stock stacked in the oven; and
  - an upwardly moving plunger mounted near the stop for pushing one bar of stock over the stop and into position for injection into the barrel.
34. A furnace for the continuous heating of objects comprising:
- a substantially horizontal, rotatably mounted, barrel having an object inlet end and an object outlet end;
  - means for at times rotationally driving the barrel; and
  - heating means at the outlet end for supplying heat into the outlet end;
- wherein a preheat oven having an inlet end and an outlet end is provided and has its outlet end connected to the inlet end of the barrel; objects introduced into the inlet end of the preheat oven move from the inlet end of said preheat oven to the outlet end thereof; means are provided for moving the objects from the outlet end of said preheat oven into the inlet end of the barrel; and
- means are provided for conducting heated gases emerging from the inlet end of said barrel into and through the preheat oven whereby said objects are preheated by said heated gases which have flowed from the outlet end of said barrel to the inlet end thereof and then from the outlet end of said preheat oven to the inlet end thereof.
35. A furnace according to claim 34, wherein the preheat oven is stationary, is mounted to abut the inlet end of the barrel, and is inclined to rise therefrom; and
- wherein said objects may be stacked and after being preheated by hot gases flowing from the outlet end of the barrel, are moved into the object inlet end of said barrel.
36. A furnace according to claim 20, wherein the means adjacent the outlet end of the barrel for receiving objects is provided with a trap door.
37. A furnace according to claim 36, wherein the trap door has hinges and the axis of hinges of the trap door is substantially horizontal and substantially parallel to the rotative axis of the rotatable barrel.
38. A furnace for the continuous heating of objects comprising:
- a substantially horizontal rotatably mounted barrel having an object inlet end and an object outlet end;
  - means for at times rotationally driving the barrel; and
  - heating means at the outlet end for supplying heat into the outlet end;
- wherein the barrel is provided with a core having a plurality of passages formed therethrough;

- wherein one of the passages is located on the rotative axis of said barrel and at least one of said passages is offset from the rotative axis.
39. A furnace according to claim 38, wherein the axial passage has a larger diameter than the offset passage.
40. A furnace for the continuous heating of objects comprising:
- a substantially horizontally mounted chamber having an inlet end and an outlet end and formed with a plurality of substantially horizontal longitudinal passages through which objects may pass from one end to the other;
  - means for at times causing longitudinal movement of the objects along the chamber in at least one of said passages from the inlet end toward the outlet end;
  - means adjacent the outlet end of the chamber for receiving objects from the chamber; and
  - means for supplying heat into the furnace in at least two streams, at least one of said streams being a stream of reducing gas supplied into at least one of said longitudinal passages and the other stream being a stream of oxidizing gas supplied into at least one of the other of said longitudinal passages.
41. A furnace according to claim 40, wherein the chamber is formed with transverse passages spaced from the outlet end of the chamber for mixing the streams of reducing gas and oxidizing gas.
42. A furnace for the continuous heating of objects comprising:
- a substantially horizontally mounted chamber having an inlet end and an outlet end and formed with a plurality of substantially horizontal longitudinal passages through which objects may pass from one end to the other;
  - means for at times causing longitudinal movement of the objects along the chamber in at least one of said passages from the inlet end toward the outlet end;
  - means adjacent the outlet end of the chamber for receiving objects from the chamber; and
  - means for supplying heat into the furnace; in which one of the passages is a central passageway and in which all passageways except the central passageway have their longitudinal axes in a circle which is concentric with the longitudinal axis of the central passageway.
43. The structure of claim 22, wherein the oxidizing flame comprises a lean mixture of air and gas where there is approximately 10 percent excess of air over a balanced mixture of air and gas which would achieve neutral oxidation-reduction and the reducing flame comprises a rich mixture of air and gas where there is approximately a 50 percent excess of gas over said balanced mixture of air and gas.
44. The structure of claim 43, where the rich mixture has an excess of gas of 55 percent.
45. The structure of claim 43, wherein the volume of the lean mixture is approximately five times the volume of gas having the rich mixture.
46. A furnace according to claim 20, wherein

- a. a preheat oven is mounted to abut the inlet end of the barrel; and
  - b. an inclined platform associated with said oven and extending radially upwardly and outwardly from the axis of the barrel;
- whereby said objects may be stacked on the platform and preheated in the preheat oven by hot gases flowing from the barrel.

47. A furnace according to claim 22,

wherein there is means for directing the oxidizing flame longitudinally approximately along the rotational axis of said barrel and means for directing the reducing flame longitudinally approximately along an outer portion of the barrel.

48. A furnace for the continuous heating of objects comprising:

1. a substantially horizontally mounted chamber having an inlet end and an outlet end and formed with a plurality of substantially horizontal longitudinal passages through which objects may pass from one end to the other;
2. means for at times causing longitudinal movement of the objects along the chamber in at least one of said passages from the inlet end toward the outlet end;
3. means adjacent the outlet end of the chamber for receiving objects from the chamber; and
4. means for supplying heat into the furnace; wherein

- a. the chamber comprises a rotatable mounted barrel, said barrel being formed with a central passageway extending longitudinally substantially along the rotational axis of said barrel and with a plurality of longitudinal passageways positioned outwardly of said barrel all at equal distances from said central passageway;
- b. means is provided for, at times, rotationally driving the barrel; and
- c. heating means is provided at the outlet end for supplying heat into the central passageway at the outlet end of the barrel and for supplying heat into at least one of the outwardly positioned passageways.

49. The structure of claim 48 in which one of the heating means supplies an oxidizing stream of heat and the other heating means supplies a reducing stream of heat.

50. The structure of claim 49,

wherein the oxidizing stream is supplied to the central passageway and the reducing stream is supplied to an outwardly positioned passageway.

51. The structure of claim 3, in which transverse passageways are provided connecting the central longitudinal passageway with the outwardly positioned longitudinal passageways for the purpose of mixing the oxidizing gas and the reducing gas to achieve complete combustion.

52. The structure of claim 51, wherein the transverse passageways are provided downstream from the burner and where the object

5

temperature is low enough to avoid oxidation of the objects being heated.

53. A method of heating objects comprising:

- a. heating said objects at a relatively low temperature by a stream of products of combustion of an approximately stoichiometric mixture of air and gas;

- b. continuing said heating of said objects to a relatively high temperature by a stream of products of combustion which compose a reducing mixture of air and gas.

54. A furnace for the continuous heating of objects comprising:

- a. a substantially horizontal chamber having an inlet end and an outlet end;
- b. means for at times causing movement of objects being heated from the inlet end toward the outlet end of said chamber; and
- c. means for producing two streams of heating gas one of which is an oxidizing stream and the other of which is a reducing stream wherein the oxidizing stream is directed along a path in which it does not contact the objects which are at a relatively high temperature and wherein the reducing stream is directed along a separate path to surround the objects which are at a relatively high temperature.

55. A refractory furnace liner for use in an outer furnace shell, the liner comprising:

- a. a hollow refractory core comprising (1) and inner wall portion defining the inner wall of the furnace, and (2) outwardly extending spaced legs extending into contact with said shell for rigidly supporting the core in the shell; and
- b. insulation in the spaces between the legs and between said inner walls and said shell.

56. A furnace liner according to claim 55 wherein the shell is cylindrical and rotatable and the liner comprises a series of identical inserts mounted in end to end relationship longitudinally along the cylindrical shell.

57. A furnace for the continuous heating of objects comprising:

- a. a substantially horizontal chamber having an inlet end and an outlet end and having a plurality of passageways extending from the inlet end to the outlet end;
- b. means for supplying heat to said passageways to heat objects which may be therein;
- c. means for inserting any object to be heated in one of said passageways and for pushing objects already being heated in said passageway toward and out of the outlet end of said chamber; and
- d. means for inserting an object to be heated into a second of said passageways with disturbing objects in said first named passageways and for pushing objects already being heated in said second passageway toward and out of the outlet end of said chamber.

UNITED STATES PATENT OFFICE
CERTIFICATE OF CORRECTION

Patent No. 3,816,064

Dated June 11, 1974

Inventor(s) Sigdon A. Eliot

It is certified that error appears in the above-identified patent and that said Letters Patent are hereby corrected as shown below:

column 3, line 9: "so as to shown the" should read
--- so as to show the ---;

column 4, line 13: "would direct a reading flame" should read --- would direct a reducing flame ---;

column 9, lines 54-55: "contacts T1B de-energizes the relay TLL" should read --- contacts T1B de-energizes the relay RLL ---;

column 13, lines 37-38: "Although the mixture of the oxidizing stream and the reducing stream." should be deleted;

column 13, line 60: "which consists of an excess of air gas, for example" should read
--- which consists of an excess of air as, for example ---;

column 14, lines 13-14: "screws 416, etc. extend" should read --- screws 426, etc. extend ---;

column 15, line 65: "therein said objects" should read --- wherein said objects ---.

Signed and sealed this 19th day of November 1974.
